UNITED STATES PATENT OFFICE

MARSHALL T. DAVIDSON, OF BROOKLYN, NEW YORK.

TRIPLE-EXPANSION ENGINE.

SPECIFICATION forming part of Letters Patent No. 376,639, dated January 17, 1888.

Application filed April 9, 1887. Serial No. 234,273. (No model.)

To all whom it may concern:

Be it known that I, MARSHALL T. DAVIDSON, a citizen of the United States, residing at Brooklyn, Kings county, New York, have invented certain new and useful Improvements in Triple-Expansion Engines, of which the following is a specification.

My invention relates to that class of steam-engines in which the exhaust-steam from a high-pressure engine or cylinder is used expansively in another cylinder; and my invention consists in providing the engine with three cylinders axially in line, and in supporting and arranging said cylinders, and in connecting the valves and otherwise constructing the engine so as to increase its efficiency and facilitate its construction and operation.

In the drawings, Figure 1 is a sectional side elevation of a compound pumping-engine embodying my invention. Fig. 2 is a plan view. Fig. 3 is a sectional plan.

The bed A of the engine has a support, B, for the central low-pressure cylinder, C, of the engine, and when the engine is a pumping-engine the bed also supports the pump-cylinder, (not shown); but when the latter is not employed the pillar-blocks of the engine crank-shaft may be arranged upon the bed.

The rear head, 1, of the cylinder C is bolted in place, as usual, and to the said head is secured a bracket, 2, bolted at the outer end to the inner head of a high-pressure cylinder, E, which is thus supported by and in line with the cylinder C and independently of the bed.

To the forward head, 3, of the cylinder C is secured another but smaller low-pressure cylinder, F, the high-pressure cylinder E and the two low-pressure cylinders being in line axially, and the central cylinder thus supporting both of the other cylinders. All of the cylinders are of the same length.

The cylinder F is provided with a piston, 4, and central piston-rod, 7, connected to or carrying a cross-head, 9, and to the latter are attached the two parallel piston-rods 8 of the piston 5 of the middle cylinder, C, which extend through packing-boxes on that part of the head 3 which is outside the periphery of the forward cylinder. The piston 6 of the high-pressure cylinder E is connected by a rod, 10, axially arranged, with the piston 5 of the

cylinder C, so that all the pistons move in unison and have the same stroke.

The cylinders F C E are provided, respectively, with valve chests 12 13 14 and with suitable valves and ports, and the exhaust-port of the high-pressure cylinder E is connected by a pipe, 15, with the inlet-port of the forward chest, 12, and the exhaust-port of the latter is connected by a pipe, 16, with the inlet-port of the central chest, 13, and the valves are so controlled that the steam, after doing its work in the cylinder E, is exhausted into the forward cylinder, F, and there further expands and acts to move the piston 4, and after its escape from the cylinder F it further acts upon the piston of the largest cylinder C. By this construction I secure a direct-acting triple-expansion engine with all the cylinders axially in line.

As the high-pressure cylinder is supported by the bracket 2 at a distance from the middle cylinder, easy access may be had to the stuffing-boxes of both cylinders, and the cylinder E can be disconnected without disturbing the other parts of the engine, while the forward cylinder, F, can be removed and replaced without changing the position of the central cylinder, and as the latter only is directly connected with the bed-plate, the removal of the other cylinders does not necessitate any alteration in the bed-plate connections.

While any suitably constructed and connected valves may be employed, I prefer to operate one valve from the other.

In the construction shown the valve of the forward cylinder, F, is operated by steam-pressure controlled by a rock-shaft, 17, as in the valve patented February 12, 1884, No. 293,243.

The valve-rod 18 of the cylinder F is connected to and operates the valve of the cylinder C, and a valve-rod, 19, from the latter valve is connected to operate the valve-rod 20 of the high-pressure-cylinder valve.

When it is desired to vary the throws of the valves—as, for instance, to use a valve with shorter stroke on the high-pressure cylinder—I construct the connections to secure this result. Thus the valve-rod 19 is connected by a link, 21, to a lever, 22, pivoted to the bracket 2 at the lower end, and connected by a link,

23, pivoted to the lever centrally with the spindle 20 of the high-pressure valve, which thus has half the stroke of the other valves and derives its motion therefrom. The shaft 17, controlling the valve of the forward cylinder, derives its motion from the cross-head 9 through the medium of a crank-arm, 25, and connecting-rod 27. All the valves are thus driven by a single valve-connection, the valve of the initial engine being moved from that of the secondary engine, and the stroke of either may, by like means to those described, be varied from that of the others to any extent desired. The prime mover, however, of the valve-motion can be operated from either valve chest, as is obvious.

The engine, if loaded, could not be started from a state of rest by admitting the high pressure only to the initial or high-pressure engine. I therefore connect the steam inlet-pipe 29, (which communicates with the valve-chest 14 and has the usual throttle, 30,) by a pipe, 31, provided with a valve, 32, with the exhaust port or pipe of the cylinder E, so that by opening the valve 32 the steam may be directed under full pressure to the secondary cylinder F, and after the engine is started the steam may be cut off directly from the secondary cylinder and admitted to the cylinder E.

30. Live steam may be admitted to any one or more of the cylinders when starting by the introduction of suitable pass-over valves connecting all or any of the cylinders, as is apparent.

35. When it is decided to work two of these triple-expansion direct-acting engines in double or duplex form, the valve-motion will be operated and the service of the pumps, if the

engine be used for pumping, be changed from single to duplex, in the manner described in 40 the aforesaid patent.

Without limiting myself to the precise construction and arrangement of parts shown, I claim—

1. The combination, in a triple-expansion engine, of a large cylinder, C, supported upon the bed, and two smaller cylinders, one at each end of cylinder C and axially in line therewith, and supported wholly thereby, substantially as described.

2. The combination of the cylinder C, cylinder F, supported by one head of said cylinder, and a third cylinder connected by a bracket with the other head of the cylinder C, substantially as described.

3. A triple-expansion direct-acting engine provided with three cylinders axially in line, the pistons of the center and forward engines connected by independent rods with the cross-head, and the rear and high-pressure cylinder 55 connected with the piston of the center cylinder, substantially as described.

4. The combination of the three axially-arranged cylinders with valves, one connected to be operated from a moving part of the engine, and connections between the other valves constructed to vary the throws of the valves, substantially as described.

In testimony whereof I have signed my name to this specification in the presence of two subscribing witnesses.

MARSHALL T. DAVIDSON.
